V. CARONTI

PERFORMANCE PEDESTAL

Filed April 13, 1923

Inventor:
Virgilio Caronti,
by A. J. Guadano

UNITED STATES PATENT OFFICE.

VIRGILIO CARONTI, OF CHICAGO, ILLINOIS.

PERFORMANCE PEDESTAL.

Application filed April 13, 1923. Serial No. 631,756.

To all whom it may concern:

Be it known that I, VIRGILIO CARONTI, a citizen of the United States of America, and a resident of Chicago, in the county of Cook 5 and State of Illinois, have invented certain new and useful Improvements in Performance Pedestals, of which the following is a specification.

This invention relates to that type of 10 pedestals used in acrobatic, equilibristic and like stage performances, with the parts of a disconnectible construction affording compact storage. And the present improvements have for their objects.

15 To provide a structural formation and combination of parts in a sectional disconnectible performance pedestal in which is combined lightness with great rigidity when assembled, and with compact storage and 20 effective transportation when disassembled.

25 To provide an effective journal connection between the tubular post of the pedestal and the revoluble rest or platform for the performer, to attain an effective turning action, with substantial support during such operation, all as will hereinafter more fully appear.

In the accompanying drawing:—

Fig. 1, is a perspective view illustrating 30 the general arrangement of parts in the preferred form of the invention.

Fig. 2, is an enlarged fragmentary central section of the tubular post and accessories.

Like reference numerals indicate like 35 parts in both views.

As represented in the drawing, the main tubular post 1 of the apparatus when in actual use is adapted to have bearing at its lower end on the surface of the stage floor, 40 and is rigidly held in a vertical position by a plurality of diagonal guy ropes 2 attached at one end to the upper portion of the post 1 and at their other ends to the stage floor in the usual disconnectible manner. As usual 45 in this class of apparatus, the guy ropes 2 are provided with turn buckles 3 by which they are tensioned during an erection of the apparatus to attain the desired rigidity in the same. In the present improvement the 50 tubular post 1 is formed by a plurality of sections, usually three in number, adapted for end to end connection in a rigid and substantial manner by detail formations as follows:—

55 As shown in Fig. 2, a length of tubing 4 is fixedly attached in the end bore of a post

section and projects beyond the same for slip engagement in the end bore of an adjacent post section, with a turning movement of one section independent of the other section, prevented by an angular projection 5 at the end of one section engaging with a correspondingly formed angular recess 6 in the end of the adjacent section.

A rest or platform 7 for the performer 65 or performers, and preferably of a disk form, is revolvably mounted on the upper end of the tubular post 1 by means of collar plate 8 fixed on the under side of the rest 7, and provided with a depending skirt portion 9 adapted to encircle the upper end of the post 1, and with a central depending tubular spindle 10 adapted to fix and have bearing in the upper end of the bore of the post 1 as shown.

An ornamental false work, usually a fountain structure 11, is associated with the main and lower portion of the post 1 to impart an ornamental appearance to the apparatus, and in the present construction afford means 80 for holding the post 1 in an upright condition in an operation of moving the apparatus from place to place on the floor of the stage. To such end the fountain structure 11, is provided with a central vertical passage 85 for the post 1, to hold the same upright in the above mentioned movement of the apparatus from place to place. In addition the fountain structure 11 is provided with supporting casters 12 on its bottom surface, 90 and with a horizontally movable shelf or plate 13, which is moved beneath the lower end of the main tubular post 1, to support the same above the floor in a movement of the apparatus into and out of position at the 95 center of the stage before and after a performance.

Having thus fully described my invention what I claim and desire to secure by Letters Patent, is:—

1. In a performance pedestal for acrobatic and like exhibitions, the combination of a tubular post the lower end of which is adapted to rest upon the floor, guy ropes for holding the post in a vertical position, a platform revolvably mounted at the upper end of the post by a plate on the underside of said platform, with said plate having a depending sleeve portion encircling the upper end of the post and a vertical spindle 105 fitting and turning in the upper end of the bore of said post.

2. In a performance pedestal for acrobatic and like exhibitions, the combination of a tubular post formed by aligned sections, means for connecting said sections together, 5 guy ropes for holding said post in a vertical position, and a disk like platform revolvably mounted on the upper end of said post.

3. In a performance pedestal for acrobatic and like exhibitions, the combination of a 10 tubular post formed by aligned sections, means for connecting said sections together, the same comprising a tubular extension on one section fitting the bore of an adjacent 15 section and an angular projection on the end of one section fitting an angular recess in the end of the other section, guy ropes for holding said post in a vertical position, and a disk like platform revolvably mounted on 20 the upper end of said post.

4. In a performance pedestal for acrobatic and like exhibitions, the combination of a tubular post the lower end of which is adapted 25 to rest on the floor, guy ropes for holding the post in a vertical position, a platform

revolvably mounted on the upper end of the post, and a false structure surrounding the lower portion of said post and provided with a horizontally sliding plate adapted for engagement beneath the lower end of said post 30 to support the same away from the floor in a movement of the apparatus from one place to another.

5. In a performance platform for acrobatic and like exhibitions, the combination of a 35 tubular post formed by aligned sections, means for connecting said sections together, guy ropes for holding said post in a vertical position, a disk like platform revolvably mounted on the upper end of said post, and 40 a false structure surrounding the lower portion of said post and provided with a horizontally sliding plate adapted for engagement beneath the lower end of said post to support the same away from the floor in a 45 movement of the apparatus from one place to another.

Signed at Chicago, Illinois, this 9th day of April, 1923.

VIRGILIO CARONTI.
